ROTATABLE SKEWER

Walter Koziol, Russell, Ill., assignor to Charmglow
Manufacturing Co., Antioch, Ill., a corporation of Illinois

Filed Aug. 16, 1967, Ser. No. 8,286

Term of patent 14 years

(Cl. D81—10)

Fig. 6

The dominant features of my design reside in the portions shown in full lines. The broken line showing of the screw clamps in all of the figures is for illustrative purposes only, and the skewer is omitted in FIGURES 2 through 5 for convenience of illustration.

What is claimed is:

The ornamental design of a rotatable skewer, substantially as shown and described.
